COMBINED BOTTLE AND JAR OPENER

James L. Hyale, Chicago, Ill., assignor to Ekco Products
Company, Chicago, Ill., a corporation of Illinois

Application September 9, 1954, Serial No. 32,211

Term of patent 14 years

(Cl. D44—29)

Fig. 6.

Fig. 7

Fig. 1 is a top plan view of a combined bottle and jar opener showing my new design.

Fig. 2 is a side elevational view thereof.

Fig. 3 is an end elevational view as the article appears when viewed from the left hand side of Fig. 1.

Fig. 4 is an end elevational view as the article appears when viewed from the right hand side of Fig. 1.

Fig. 5 is a sectional view taken on line 5—5 of Fig. 1.

Fig. 6 is a similar view taken on line 6—6 of Fig. 1.

Fig. 7 is a similar view taken on line 7—7 of Fig. 1.

I claim:

The ornamental design for a combined bottle and jar opener, as shown.
